UNITED STATES PATENT OFFICE.

JAMES F. HINES, OF CLEVELAND, OHIO, ASSIGNOR, BY DIRECT AND MESNE ASSIGNMENTS, OF ONE-THIRD TO JOHN M. SARVER AND ONE-THIRD TO JOSEPH K. BYE, BOTH OF COLUMBUS, OHIO.

CURTAIN-POLE.

1,278,347.

Specification of Letters Patent. Patented Sept. 10, 1918.

Application filed October 4, 1915. Serial No. 53,918.

To all whom it may concern:

Be it known that I, JAMES F. HINES, a citizen of the United States, residing at Cleveland, in the county of Cuyahoga and 5 State of Ohio, have invented certain new and useful Improvements in Curtain-Poles, of which the following is a specification.

The invention relates to poles for hanging curtains, draperies and shades at the top 10 of a window, and the object of the improvement is to provide a pivotal support for one end of a curtain pole which permits the curtain to be uniformly draped without obstruction from end to end of the pole, and 15 also permits the pole with the curtain thereon to be swung on its pivoted end away from the window without binding or bunching the curtain or impinging the window frame at the pivoted end of the pole.

20 Further objects of the improvement relate to means for detachably supporting a drapery pole adjacent to the curtain pole by means of bracket arms on the ends thereof, and also to means for supporting a shade 25 pole at one side of the curtain pole by means of shade fixtures secured on the side of the curtain pole.

These objects and other advantages are attained by the construction and arrangement 30 illustrated in the accompanying drawing, forming part hereof, in which—

Figure 1 is a plan view of the improved curtain pole showing a drapery pole and a shade pole secured thereto;

35 Fig. 2, a perspective view showing the curtain pole and the drapery pole and the supporting arms at the ends thereof;

Fig. 3, a fragmentary face view of the curtain pole showing its pivotal support in 40 section;

Fig. 4, a plan view showing the method of securing the drapery pole arm on the pivoted end of the curtain pole;

Fig. 5, a section of the curtain pole showing one shade fixture secured thereto;

Fig. 6, a section of the curtain pole showing a complementary shade fixture secured thereto;

Fig. 7, a fragmentary face view showing 50 a modified form of the pole end cap; and

Fig. 8, a plan view showing the use of two curtain poles and drapery poles mounted one on each side of a window.

Similar numerals refer to similar parts 55 throughout the drawings.

The pivotal support 1 for the curtain pole, includes the supporting bracket 2 secured to one side of the window frame, and the pole bracket 3 secured on one end of the curtain pole.

The supporting bracket is preferably formed with the base plate 4 having ears 5 on each side with slots or apertures 6 therein, for securing the bracket to the side of the window by means of the screws 7.

The supporting bracket is also formed with the forwardly extending shank 8 which is made of sufficient vertical depth to rigidly sustain the supporting head 9, which is formed on the forward end of the stem.

The vertical journal bearing or socket 10 is formed in the head of the supporting bracket and is made of such a substantial length as will securely support the pivot stem 11 of the pole bracket.

The pole bracket 3 is formed with the pendent pivot stem 11 which is made to neatly fit and rotate in the journal bearing 10 in the supporting head, and at the upper end of the pivot stem is formed the annular shoulder 12 adapted to bear and rotate upon the upper end 13 of the supporting head.

The body 14 of the pole bracket is formed with a relatively short arm 15 or 15^a on one side of the pivot stem and with the relatively long arm 16 on the other side of the pivot stem; which arms are respectively adapted to engage and support one end of the curtain pole 17.

The short arm 15 of the pole bracket is provided with the cylindric socket 18 adapted to receive and engage the end portion of the curtain pole 17. This arm is formed as a ring through which the end of the curtain pole protrudes a short distance.

The body portion 14 and long arm 16, of the pole bracket are cylindrically concaved on their upper side, coaxial with the cylindric socket formed in the short end thereof, thus forming a supporting seat for a considerable portion of the curtain pole extending a substantial distance along the under side thereof from the pivot axis of the pole bracket.

The top and sides of the body portion and long arm of the pole bracket are cut away so as to freely expose the sides and the top of the curtain pole, excepting only the extreme end thereof which is entered and secured in the cylindric socket in the short arm of the

bracket. By this formation of the bracket it is evident that a curtain may be uniformly draped upon the pole throughout its entire length without being obstructed or interfered with by the pole bracket. A suitable aperture 19 is preferably provided in the end of the long arm of the bracket, through which aperture a screw 20 may be passed for securing the pole in the seat and socket formed by the pole bracket.

The parts are so proportioned and arranged that the extreme length of the short arm of the pole bracket is only about half the length of the shank of the supporting bracket, as shown in broken lines in Fig. 5, so that the free end of the pole can be rotated directly outward without any portion of its pivotal bracket impinging the frame of the window; and it is also evident that a curtain may be draped over and beyond the extreme end of the pole and its pivotal bracket, and made fast to the window frame, without being bunched or crushed against the window frame when the free end of the pole is swung away therefrom.

The long arm of the pole bracket is extended a substantial distance along the under side of the pole to give sufficient leverage, with reference to the end of the pole which is secured in the short arm of the bracket, so as to firmly sustain the free end of the pole from sagging, excepting as the pole may bend from its own elasticity. Such an extension of the long arm of the pole bracket is made to compensate for the necessity of making the other arm short enough to permit the bracket and the curtain draped thereover to swing inward without impinging or bunching against the window frame.

The cylindric seat in the pole bracket is preferably inclined upward from the short arm to the long arm thereof, with reference to the vertical axis of its pivot stem, as shown more clearly in Fig. 3, so as to compensate for any bending there may be in the body and free end of the pole by reason of its elasticity or any looseness there may be in the pivotal bearing; and it is evident that by this construction the free end of the pole will always be maintained at the same height as the pivoted end thereof.

A suitable keeper 21 may be secured to the opposite side of the window frame for normally receiving and holding the free end of the curtain pole from swinging away from the window, and it is preferred to use such a keeper when a single pole is used extending entirely across a window, as shown in Fig. 1; but the use of such a keeper is not usually necessary where a pair of comparatively short poles are pivoted, one on each side of a window, as shown in Fig. 8.

The drapery pole 22 is mounted at one side of the curtain pole 17 by means of the brackets 23 and 23^a secured on the ends of the

curtain pole 17. The body portion 24 and 24^a of these brackets are preferably formed semi-spherical in shape with a suitable cylindric recess 25 fitting over the ends of the curtain pole, to which they may be secured by means of screws 26 entered through the brackets into the ends of the pole.

The bracket 23 on the pivoted end of the curtain pole may be fixed from rotation thereon by providing the concave recess 27 in the rim of its head 24, which recess is adapted to fit around the curved end 28 of the short arm 15 of the pole bracket, as shown in Figs. 2, 3 and 4; and the bracket 23^a on the free end of the curtain pole may be fixed from rotation thereon by means of the tongue 29 bent from the end of the pole, and engaged in the recesses 30 provided in the rim of the head 24^a of the bracket.

Each end bracket is provided with the forwardly projecting arms 31 having inturned flanges 32 thereon forming sockets 33 adapted to receive and support the ends of the drapery pole 22. The flanges 32 are provided with the notches 34 on the upper side of the arms adjacent to the head of the bracket, through which notches the ends of the drapery pole are adapted to be entered into and withdrawn from the sockets 33.

By these means it is evident that the drapery pole, with the drapery thereon, can be readily mounted alongside the curtain pole, and can also be readily removed therefrom, without disturbing the drapery or the curtain, and without the use of screws or other securing means.

The shade pole 35 is mounted at the other side of the curtain pole by means of the fixtures 36 and 36^a having the usual journal bearing 37 and journal notch 37^a in their free ends, and the semi-cylindric flanges 38 on their other ends adapted to embrace and be secured to the under inner side of the curtain pole, as by means of the screws 39.

By mounting the drapery pole and the shade pole at the sides of the curtain pole, it is evident that these poles with the drapery and curtain thereon can be readily swung to and from the window with the curtain pole, without in any manner affecting the use of the curtain pole as described above.

I claim:

1. The combination of a supporting bracket having a bearing socket therein and adapted for attachment to one side of a window frame, a bracket having a depending pivot shank fitting in the bearing socket, a pole attached to the bracket, and a shade fixture carried solely by the pole.

2. The combination of a curtain pole, and brackets fitting on and supported solely by the ends of the pole and having forwardly projecting arms with inturned ends, and a drapery pole supported at its ends by the inturned ends of said arms.

3. The combination of a curtain pole having brackets supported solely on its ends with forwardly projecting arms having in-turned flanges thereon, and a drapery pole supported at its ends by said flanges. 5
4. The combination of a curtain pole having brackets supported solely on its ends with forwardly projecting arms having in-turned flanges thereon, and a drapery pole supported at its ends by said flanges, there 10 being notches in the flanges on the upper sides of the arms for passing the ends of the drapery pole.
5. A pivotal support for the end of a curtain pole including a supporting bracket having a shank with a head thereon, and a pole bracket having a pendent stem pivoted on the supporting head with a relatively 15
- short arm for engaging one end of the curtain pole and a relatively long arm forming 20 a seat for the curtain pole extending a substantial distance along its under side from the axis of the pivot stem, the short arm being in the form of a ring through which the end of the curtain pole may be passed and 25 protruded.
6. A bracket for a curtain pole comprising a pendent pivot stem, a relatively short arm engaging one end of the curtain pole and a relatively long arm forming a seat for the 30 curtain pole extending a substantial distance along its under side from the axis of the pivot stem, the short arm being in the form of a ring through which the end of the curtain pole may be passed and protruded. 35

JAMES F. HINES.
